UNITED STATES PATENT OFFICE.

ANDERSON D. HOLLAND, OF NEWPORT, ARKANSAS.

COMBINED LOCK AND LATCH.

SPECIFICATION forming part of Letters Patent No. 293,248, dated February 12, 1884.

Application filed January 4, 1883. (Model.)

To all whom it may concern:

Be it known that I, ANDERSON D. HOLLAND, a citizen of the United States, residing at Newport, in the county of Jackson and State of Arkansas, have invented certain new and useful Improvements in Locks; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a face view of my lock, with the face-plate removed and unlocked. Fig. 2 is a similar view, showing same in a locked position.

This invention has relation to improvements in door-locks; and it consists in the construction and novel arrangement of parts, as will be hereinafter more fully set forth and claimed.

In the accompanying drawings, the letter A designates the lock-case, which may have the ordinary rectangular form, the opening B, for the toe of the bolt, being made in the lower part of the front end.

Within the case, and extending downward to the opening B, is formed an oblique slideway, C, which is bounded by the lateral walls of the case and by the oblique front and rear guide-pieces, D and E.

Communicating with the upper portion of the oblique slideway, and extending rearwardly therefrom, is a horizontal slideway, F, whereof the lower guide-pieces, G and H, are separated, or so arranged as to form an opening, K, into the horizontal slideway above the key-hole L.

In the oblique slideway is seated the oblique reciprocating bolt N, the length of which is such that when it is fully projected there will be an interval, m, above it equal to the breadth of the slideway F between its upper and lower guides. When the bolt is withdrawn obliquely upward into the case, the interval m will be filled by the upper end of the bolt.

In the horizontal slideway is seated the locking-slide P, the front end of which, when said slide is withdrawn, does not project into the oblique slideway, but is flush, or nearly so, with the guide-piece E thereof. The slide P

is recessed from below upward, to receive a vertically-adjustable bar, S, which is held in a depressed position by a spring, V, in the slide. 55 The bar S is provided with one or more end studs, a, which project downward to engage the perforations b in the guide-pieces G and H, or either of them. The perforations b are arranged in pairs, one in front of the other, so 60 that one will receive the stud a when the slide is withdrawn, and the other will receive said stud when the slide is projected or in the locking position. A notch or bearing, c, is made in the bottom of the slide P, to engage the bit 65 of the key.

In the lower rear portion of the oblique bolt N is made a notch or bearing, d, which engages an arm, e, of the knob-shaft g, so that when the shaft is turned the bolt can be raised 70 and withdrawn or lowered and projected, according to the direction of rotation. When the oblique bolt is projected, it is fastened in position by moving the locking-slide P forward over the upper end of said bolt. This is 75 accomplished by means of the key, which, when turned, first raises the bar S, disengaging its stud or studs, and then pushes the slide forward, when it becomes again fastened by the descent of the bar and re-engagement 80 of its stud or studs. A reverse movement of the key will withdraw the slide, relieving the oblique bolt, which can then be withdrawn by means of the knob-shaft and arm. The toe of the bolt is obliquely beveled, so that it will be 85 pushed back automatically, when it engages an obliquely-beveled bearing of the keeper.

Reciprocating bolts operated by means of arms on the knob-spindles engaging in notches or recesses in the bolts have been heretofore 90 used in locks, and diagonally-moving bolts being old, I do not claim either of them, broadly; but

Having described this invention, what I claim, and desire to secure by Letters Patent, 95 is—

1. In a door-lock, the oblique reciprocating bolt, having its opposite ends beveled, whereby the said bolt will rise automatically in closing the door, in combination with the knob-shank and arm engaging the notches of the bolt, substantially as specified.

2. The door-lock herein described, consisting of the case having the communicating ob-

lique and horizontal slideways, the oblique reciprocating bolt, having its ends beveled, and the horizontal locking-slide over the key-hole, the knob-shaft, and its arm engaging a 5 notch or bearing of the oblique bolt, all combined and adapted to operate substantially as specified.

In testimony whereof I affix my signature in presence of two witnesses.

ANDERSON D. HOLLAND.
